ABSTRACT: An actuating device on a sewing machine for a binding apparatus used for forming and sewing a tubular binding containing a rubber band on a piece of clothing. A horizontal base plate has mounted thereon a fixed guide part and a slidable guide part, the latter moving under the action of a horizontal operating rod arranged below said base plate into an open position to receive between said guide parts the binding and the edge of clothing to be sewed together. The movement of said slidable part is controlled by a cylindrical control member mounted on said operating rod and having recessed cam guides therein, into which extends a guide pin fixed to said base plate. Only a short push on one end of the operating rod by a knee-operated lever is required to move the slidable guide part into its open position and to arrest it in this position.

ACTUATING DEVICE ON SEWING MACHINES FOR A BINDING APPARATUS

The invention relates to an actuating device on sewing machines for a binding apparatus provided with a stationary and a movable guide-part and used for forming and sewing a binding on a piece of clothing. The apparatus is equipped with an operating rod connected with the movable guide-part, and is slideable in its lengthwise direction and actuated by a pivoted lever against the action of a return spring.

In the production of bindings from tubular fabrics, it is necessary to insert the tubular band which has a rubber ring inserted therein individually into the binding apparatus and then guide it together with the piece of clothing to the place where the sewing is to take place. A binding apparatus is known which consists of a stationary guide-part serving as a material abutment and a movable guide-part comprising a slideable part. In addition, there is present also a hand flap for the opening of the binding apparatus. Before the tubular band can be inserted with its inserted rubber ring in the mentioned apparatus, first the hand flap must be grasped and by pivoting the same, the binding apparatus is opened. At the same time, by the actuation of a lever, which may for example be constructed as knee-operated lever, the slideable part must be brought from its closure position to its opening position. In addition, the pressure-foot of the sewing machine must be raised by stepping on a foot-pedal. Only when these operative steps have been accomplished can the tubular band with the rubber ring therein be inserted in the binding apparatus. In this connection, it is to be noted that the knee-operated lever for holding the slideable part open must be held in position until the insertion step has been completed. Only then the knee-operated lever may be released again, whereby, after the binding edge of the piece of clothing is pushed into the tubular band, the pressure foot of the sewing machine is again lowered and the hand flap grasped anew for closing the binding apparatus and must be pivotally moved back again. Unfortunately it may happen with this known apparatus that upon a continuous operation of the knee-operated lever, for a longer period of time, and shortly before completion of the binding-finishing on an article of clothing, namely up to insertion of a new tubular band with rubber ring for the next following operative step, this knee-operated lever must remain in engagement, so that the slideable part remains in its open position. Furthermore, the hand flap is still to be pivotally operated for opening of the binding apparatus. These operations are necessary for the reason that the beginning of the almost finished seam on the binding of the piece of clothing may be guided without damage through the opened apparatus so that the seam upon further sewing of the seam may be completed. This known actuating device on the binding apparatus has the disadvantage that the knee-operated lever must remain engaged for so long, that is, it must be held by the knee, until the steps described have been completed. This retention of the knee-operated lever which is associated with a return spring, requires an overcoming of the spring force each time upon pressure with the knee during its operative stage and this results in a heavy physical strain on the sewer or seamstress. Furthermore, the constant opening and closure of the hand flap of the binding apparatus is an uneconomical operation, which requires a great deal of time during each working day.

These disadvantages are overcome by means of the present invention, which has the object of eliminating the regular holding of the actuating lever, namely, the knee-operated lever, as well as abolishing the constant actuation of the hand-flap of the binding apparatus.

This object is attained according to the invention by providing a cam-controlled mechanism which consists of a control cylinder having guide-ways and a detent in operative connection with a guide-pin in operative engagement with the detent for arresting the movable guide-part when in its open position. By means of this control mechanism, a continuous holding of the knee-operated lever can be dispensed with. In order to bring the slideable part of the binding mechanism into its open

position, it is sufficient to actuate the knee-operated lever quite briefly and immediately release it again. By means of a guide-pin which is in operative connection with the detent of the control cylinder, a sliding back of the slideable part is prevented, so that the latter remains in its open position.

The control cylinder is suitably connected with the operating rod and is provided with guide grooves or walls for engagement with the guide-pin. It is, however, also possible to arrange a guide-pin on the operating rod.

According to a particular object of the invention, the control cylinder is rotatably arranged, but not axially movably arranged on the operating rod and its cam grooves are formed by groove-shaped recesses, which provide a run-up flank and an inlet guide. A portion not milled out and arranged within the guide-rails of the controller cylinder forms the detent acting as abutment for the guide-pin disposed fixedly on a base-plate, whereby the surface on the detent receiving the guide-pin is shaped concavely. The fixed guide-pin enters the groove-shaped guides of the control cylinder when the operating rod is shifted lengthwise.

According to a further feature of the invention, the run-up flank in the control cylinder when engaging the guide-pin imparts a rotary movement to the control cylinder. This run-up flank may comprise an inclined surface, while the inlet guide groove first extends parallel to the operating-rod and thereafter extends inclined downwardly. An abutment member is provided for interrupting the sliding movement of the guide-pin within its guide-path, said abutment being located opposite the concave surface of the detent. In a further development of the invention, the control cylinder may be arrestable with the assistance of a return spring connected with the operating rod when the guide-pin engages the concave surface on the detent.

The invention is described in the following more in detail with reference to the accompanying drawing.

In the drawings:

FIG. 1 a front view of the actuating device in closed condition.

FIG. 2 a front view of the actuating device in open condition.

FIG. 3 a plan view of the actuating device according to FIG.

1, and

FIG. 4 a cutaway portion of the control cylinder shown in FIG. 3, in an enlarged view with a sectional showing of a guide-pin assuming different positions.

Referring to the drawing, the base plate 1 of a sewing-machine, not shown, has arranged thereon a fabric abutment 2 formed as stationary guide-part which cooperates with a slideable guide part 3 movable in an opening- and closure-position. The slideable part 3 is operatively connected with a horizontal operating rod 4, which is slidably supported in axially spaced bearings 5 extending below the base plate 1. The rod 4 has mounted thereon a control cylinder 6 constructed as a cam gate, said control cylinder being axially fixed but rotatable on the rod 4 so as to axially move with the same. The control cylinder 6 is provided with guide walls which are formed by groove-shaped recesses, for example, cut-outs and these guide walls serve as a run-up guide 7 as well as an inlet guide 8 and an outlet guide 9, in fact, they serve as guides for a pin 10 fixed on the base plate 1 and projecting downwardly therefrom and into the area of the guide walls. The control cylinder 6 is furthermore provided with a guide detent 11 acting as run-up flank for the guide-pin 10. The guide detent 11 is formed by a part not milled out when the guide walls 7 to 9 were formed and is provided with a concave surface 12 for receiving the guide-pin 10. The operating rod 4 has a lateral extension 4a to which is attached one end of a return spring 13, which serves for holding the guide-pin 10 in engagement with the concave surface 12 of the guide detent 11, and, after the release of the pin 10 from the guide detent 11 causes the return of the operating rod 4 and the control cylinder 6 to the starting position, whereby operatively also the slideable part 3 is brought back to its closure position. The operating rod 4 is operatively

connected with its one end 14 with a tongue 15 of a knee-operated lever 16, while the other end 17 of the rod 4 has a collar 17 thereon which engages one end of a spring 18, mounted on the rod 4, while the other end of the spring 18 engages an abutment 1a extending downwardly from the base plate 1. This spring 18 is effective in the closure position of the slideable part 3 and insures a yieldable position of the same.

The operation of the actuating device is as follows: A short pressure with the knee on the knee-operated lever 16 toward the left causes a shifting of the slideable part 3 into its opening position. Upon this brief actuation of the lever 16, the tongue 15 presses against the end 14 of the operating-rod 4, so that the latter is pushed from the position shown in FIG. 1 into the position according to FIG. 2. Upon this sliding movement of the operating-rod 4, the control cylinder 6 which is connected against axial movement, but rotatable on the operating-rod 4, approaches the guide-pin 10 fixedly attached to the base-plate 1, and is operated by the same. At first, the guide-pin 10 enters and follows the inlet-guide 8, which extends first parallel to the operating-rod 4 and thereafter extends inclined downwardly and then rearwardly, so that the pin 10 will engage an abutment 19 at the end of the inlet-guide 8. Since the actuation of the knee-operated lever 16 takes place only briefly, the return spring 13 has the tendency to move the operating-rod 4 back again into its starting position. This return movement of the spring 13 is, however, immediately interrupted again, because in the meantime the guide-pin 10 from the abutment 19 on has returned the distance γ (FIG. 3) and has engaged the concave surface 12 of the detent 11, and now performs with the assistance of the return spring 13 a stoppage of the control cylinder 6 and therewith stops the slideable part 3 connected with the operating rod 4, so that the slideable part 3 remains in its open position.

Now the tubular band with the rubber ring therein is inserted between the parts 2 and 3 of the apparatus, without the necessity of having to hold the knee-operated lever 16. By means of the suitable configuration of the slideable part 3, the hand-flap in use up to now on an apparatus of this type has become superfluous, so that in this way, the manual operations necessary for the opening and closing of the hand flap are dispensed with.

After the tubular band with rubber ring therein is inserted in the apparatus, the knee-operated lever 16 is again briefly actuated. This has the result that firstly the guide-pin 10 is urged away from the concave surface 12 of the detent 11, whereby, as it is apparent from FIG. 4, it moves along the path γ and in this way reaches the area of the outlet-guide 9. At the same time, the return spring 13 becomes active, which now moves the operating-rod 4 and the control cylinder 6 thereon back to the starting position. When this takes place the guide-pin 10 moves along the outlet guide 9 and leaves the control cylinder 6, and covers the path γ and β . At the same time, the slideable part 3 connected with the operating-rod 4 is also pushed back again into its starting position, so that it may assume its closure position shown in FIG. 1. Since the slideable part 3 is again disposed in its closure position it is now possible as soon as the inserted tubular band as well as rubber ring and the binding

edge of the piece of clothing are combined to lower the pressure foot of the sewing machine so that the sewing operation may be commenced.

An inclined surface 20 provided in the area of the run-up guide 7 serves the purpose of insuring that the guide-pin 10 positively reaches the area of the inlet-guide in case the control cylinder 6 rotates somewhat during the shifting movement of the operating-rod 4. The arrows indicated in FIG. 4 characterize the path along which the rigid guide-pin 11 moves 10 within the guides of the slideable, however, axially fixed and rotatable control cylinder 6. The arc-shaped lines indicated in FIG. 2 with α γ and β indicate the paths of movement of the knee-operated lever 16.

We claim:

- 15 1. An actuating device on a sewing-machine for a binding apparatus, comprising a stationary guide-part and a movable guide-part used for the formation and sewing of a binding on a piece of clothing, a horizontally disposed operating rod connected with said movable guide-part, means for slidably supporting said operating rod lengthwise to the longitudinal axis, a spring for urging said operating rod in one direction. An actuating lever for slidably moving said operating rod against the action of said spring, an operating means including a movable cam gate with a cam groove and a detent and a fixedly mounted guide-pin which is adapted to come into operative connection with said detent for arresting said movable guide-part in its open position.
- 20 2. Actuating device according to claim 1, in which said cam gate is mounted on said operating rod and that said cam groove forms guide walls engaged by said pin when said operating rod is shifted in one direction.
- 25 3. Actuating device according to claim 2, in which said cam gate is formed by a cylindrical control member which is rotatably but non-axially secured on said operating rod, said guide walls being formed in groove-shaped recesses in said control member and form a run-up flank, an inlet guide and an outlet guide.
- 30 4. Actuating device according to claim 1, in which said detent forms an abutment for said guide-pin which is mounted on a horizontal base plate, and that the surface on said detent receiving said guide-pin is concave.
- 35 5. Actuating device according to claim 3 in which the said fixed guide-pin when engaging said run-up flank in said cylindrical control member imparts to the latter a rotary movement, said run-up flank being formed by an inclined surface, and that said inlet guide extending first parallel to the operating rod and thereafter inclined thereto, whereby an abutment at the end of said inclined guide interrupts the sliding movement of the guide-pin within the guide path, said abutment being disposed opposite a concave surface formed on said detent.
- 40 6. Actuating device according to claim 4, in which the cylindrical control cylinder under the action of said spring which is operatively connected with said operating rod is caused to engage said concave surface on said detent and thereby is arrested against further axial movement.
